(57) **CLAIM**

The ornamental design for a fish scaling tool, as shown and described.

DESCRIPTION

FIG. 1 is a perspective view of a fish scaling tool showing my new design;

FIG. 2 is a top view thereof;

FIG. 3 is a bottom view thereof;

FIG. 4 is a right side elevational view with the left side being a mirror image thereof;

FIG. 5 is a front elevational view thereof; and,

FIG. 6 is a rear elevational view thereof.

The broken line showing of a handle in each of the figures of the drawings is for demonstrative purposes only and forms no part of the claimed design.
